UNITED STATES PATENT OFFICE.

EDMOND M. WEINAT, OF MAYWOOD, ILLINOIS, ASSIGNOR OF ONE-HALF TO WILLIAM D. KANE,
OF CHICAGO, ILLINOIS.

ROTARY EXPLOSION-ENGINE.

No. 908,916.

Specification of Letters Patent.

Patented Jan. 5, 1909.

Application filed March 30, 1908. Serial No. 424,149.

To all whom it may concern:

Be it known that I, EDMOND M. WEINAT, a subject of the Queen of the Netherlands, residing at Maywood, county of Cook, and State of Illinois, have invented certain new and useful Improvements in Rotary Explosion-Engines, of which the following is a specification.

My invention relates to rotary engines and particularly to rotary explosion engines.

The object of my invention is to provide a rotary engine which shall be of few parts and readily operated.

A further object of my invention is to provide a rotary explosion engine in which the impulse of each explosion, will condense or compress the charge for the next explosion.

A further object of my invention is to provide a rotary engine in which the exhaust shall be opened shortly after each explosion, that is as soon as the piston has received the maximum impulse therefrom, and held open until the instant of injecting a fresh charge into the explosion chamber.

A further object of my invention is to provide a rotary explosion engine which may be readily reversed and which will run as well in one direction as in the other.

Other objects will appear hereinafter.

With these objects in view my invention consists generally in a working cylinder and a piston mounted therein, said piston having a combined rotary and laterally reciprocatory movement, in combination with a shaft driven by the rotary movement of the piston, and means for operating the inlet and the exhaust by the lateral movement of the piston.

My invention further consists in a working cylinder and a compression cylinder arranged upon each side of the working cylinder and in axial alinement therewith, in combination with a shaft rotatably mounted in said cylinders, a working piston slidably mounted but rotatably fixed upon said shaft and within the working cylinder, said piston having a combined rotary and laterally reciprocatory movement, a compression piston arranged in each of the compression cylinders and rigidly fixed to said working piston and movable therewith, inlet and exhaust ports leading from said compression cylinders to the working cylinder, a valve ring arranged in said cylinders for controlling the ports, and means on the compression pistons for operating said rings at the proper time.

My invention further consists in a working cylinder, the circular end walls of which are divided into a plurality of equal sectors angularly disposed and those upon the opposite end walls being equally and oppositely inclined, and a piston coextensive in diameter with said cylinder and comprising a plate formed of a plurality of sectors conforming in number and angular arrangement to those of the end walls of the cylinder.

My invention further consists in a working cylinder and piston as above mentioned, the sectoral faces of the cylinder head each being provided with an explosion chamber and means for exploding a charge successively and alternately in the chambers of the opposite heads to drive the cylinder back and forth from one head to the other, the angular disposition of the sectors and the several explosion chambers imparting a rotary movement to the piston and shaft.

My invention further consists in various details of construction and arrangements of parts all as will be described hereinafter and particularly pointed out in the claims.

My invention will be more readily understood by reference to the accompanying drawings forming a part of this specification, and in which—

Figure 1 is a plan view of a rotary engine embodying my invention in its preferred form, Fig. 2 is a vertical central section of the engine on the line $x-x$ of Fig. 1, the piston being shown in elevation, Fig. 3 is a vertical section on the line $y-y$ of Fig. 2, Fig. 4 is a central horizontal section on the line $z-z$ of Fig. 3, the heads of the working cylinder and the piston being shown in elevation. Fig. 5 is a section on the line $m-m$ of Fig. 2, Fig. 6 is a section on the line $n-n$ of Fig. 2, Fig. 7 is a section on the line $w-w$ of Fig. 2, and Fig. 8 is an inside face view of one of the valve rings.

Referring to the drawings, 1 indicates the working cylinder formed of the jacketed cylindrical shell 2 and the cylinder heads 3 and 4. The cylinder heads are divided into an equal number of sectors 5 and 6 which are arranged at equal but opposite angles with relation to the axis of the cylinder. The faces or sectors 5 of the cylinder heads are arranged directly opposite from each other and are oppositely inclined from each other, as are also the faces or sectors 6. This is clearly seen in Fig. 4 of the drawings. Each

of the faces is provided with an explosion chamber 5' or 6' respectively, into which the explosive mixture is forced and exploded at the proper intervals. As will appear herein-
5 after but one set of chambers 5' or 6' is used at a time, one set to drive the shaft in one direction, and the other set to drive it in the opposite direction.

The working piston comprises a sectoral 10 plate 7 of substantially the same diameter as the cylinder 1, the sectors of which correspond in number and angular inclination to the faces 5 and 6 of the cylinder heads.

7^a and 7^b indicate the series of oppositely 15 inclined sectors of which the piston is composed. The adjacent edges 8 of the cylinder heads are but a sufficient distance apart to permit the piston to lie between them, hence one of the series of sectors 7^b or 7^a of the 20 piston must lie in contact with the adjacent parallel faces of the cylinder heads. When the piston is in one position its several sectors will lie flat against the several faces 5 and 6 of one of the cylinder heads, at which times 25 it will close the explosion chambers in the head.

It is obvious that an explosion in one of the chambers at this time will drive the piston against the opposite head and in position 30 to close the pockets in the latter. An explosion in one of the pockets of the latter head, will drive it back against the first. However, on account of the angular disposition of the contiguous faces at the time of 35 the explosion, the impulse of the explosion will drive the piston in an angular direction, imparting a rotary movement thereto as well as a reciprocatory movement. It is also obvious that, on account of the angular dis- 40 position of the sectoral faces of the cylinder heads and the piston and their contiguity, the piston cannot rotate except with a latter and reciprocatory movement.

Arranged upon the opposite sides of the 45 cylinder 1 and in axial alinement therewith are a pair of cylinders 9 and 10 which are preferably formed in the same casting with the cylinder heads 3 and 4. Extending centrally through the cylinders 9, 1 and 10 is 50 the main shaft 11 upon which the piston 7 is mounted. The piston is rotatably fixed to the shaft but longitudinally slidabie thereon and to this end, it is formed with a sleeve 12 by means of which it is secured to or mounted 55 upon the shaft. To decrease the friction incident to the longitudinal movement of the piston on the shaft, I provide suitable ball bearings. Accordingly, a sleeve 13 is fixed to the shaft 11 and is provided with radial 60 longitudinal ribs 14 which, together with similar ribs 15 on the inner face of the sleeve 12 form raceways for the balls 16. The ends of the cylinders 9 and 10 are closed by the respective cylinder heads 9' and 10' and the 65 sleeve 13 and ribs 14 extend from the head 9'

to the head 10'. Arranged within each of the cylinders 9 and 10 is a piston 17 and 18 respectively, which are connected to the working piston 7 and move longitudinally on the shaft therewith. The pistons 17 and 18 70 are preferably formed integrally with the sleeve 12 and the piston 7 and consequently rotate therewith. The function of the pistons 17 and 18 is to draw in the explosive mixture and compress the same prior to forcing it into the explosion chambers, hence these parts are termed the compression cylinders and compression pistons. The walls 9^a and 10^a of the compression cylinders 75 are provided with a plurality of longitudinal 80 passage ways or ports leading to the explosion chambers 5' and 6', there being a port for each of the sectoral faces of the cylinder heads.

In the drawings I have illustrated each of the cylinder heads 3 and 4 as divided into eight sectoral faces of which four are inclined in one direction and the remaining four in the opposite direction, hence I provide eight ports in each of the walls 9^a and 90 10^a. Four of the ports 19 lead to the chambers 5', the remaining ports 20 leading to the chambers 6'. Assuming that the engine is running in the direction of the arrows (Figs. 2 and 4) the chambers 5' will constitute the explosion 95 chambers. It is therefore evident that the explosive mixture must be admitted to these chambers 5' at the proper time and to them only. To this end a valve ring is provided at the outer end of each of the compression 100 cylinders which establishes communication between said cylinders and the ports at the proper time. The proper time for establishing a communication is when the compression piston is at or near the end of its compression 105 stroke, hence I utilize the motion of the piston to operate the valve ring.

21 and 22 indicate the valve rings which are arranged in the walls of the cylinders at their outer ends. The inner diameter of the 110 rings is equal to that of the cylinder and the inner face of the ring forms a continuation of the inner wall of the cylinder. The ring is provided with four ports 23 arranged quartering thereon and normally held intermediate of a pair of the ports 19 and 20. The ports 23 extend through the inner face 24 of the rings and through the face 25 into the respective cylinder 9 or 10. The rings are also provided with eight exhaust ports 26 115 which register with the ports 19 and 20 when the ring is in normal position. The ports 26 extend through the inner face 24 of the rings to register with the ports 19 and 20 and through the outer periphery 27 to discharge 120 into a common exhaust passage 28 formed in the cylinder walls.

Each ring is held in normal position by a pair of springs 29-29' arranged in a recess 30 in the cylinder walls. The springs are 130

attached to a pin 31 extending from the periphery of the ring and secured at the opposite ends to the end walls of the recess 30 as at 32. Extending inwardly from the 5 ring is a lug 33 which is engaged at the proper times by lugs 34 formed on the outer face of the pistons 9 and 10. The pistons make four longitudinal reciprocations with each revolution, hence four lugs 34 are provided which 10 successively engage the lug 33 and that at the end of each compression stroke. The heads 9' and 10' are each provided with a fuel inlet having a pop-valve 36. As the compression piston moves inwardly, it draws 15 in a charge of fuel through the inlet and upon the return stroke compresses the same, the valve 36 automatically closing. As the piston reaches the end of its compression stroke one of the lugs 34 thereon engages 20 the lug 33 and turns the ring to register the ports 23 with the ports 19, admitting the compressed explosive charge to the chambers 5'. This is clear when it is remembered that the compression pistons rotate with the working piston. The compression pistons continue to move inwardly until they close or 25 cover the ports in the ring and at the instant that the ports are closed the charges in the chambers 5' are ignited by the sparkers 37. 30 The pistons are immediately driven in the opposite direction and the operation is repeated at the opposite end of the engine. As soon as the compression piston is retracted a short distance the springs 29-29' 35 return the ring to normal position opening the exhaust which stays open until the next charge is to be forced into the explosion chamber.

To run the engine in the reverse direction 40 the explosion chambers 6' are used in which case the port 23 is moved in the opposite direction permitting the explosive charges to pass through the ports 20 to said chambers, and the sparkers 38 being employed. 45 To limit the return movement of the ring to normal position after being released the ring is slotted or grooved as at 39 and a pair of pins 40 and 41 are provided which pass through the respective cylinder head into 50 engagement with the slot. The pins are connected to a rock lever 42 in such a manner that only one can be thrown into the slot at a time, and this is determined by the direction in which the engine is running.

55 The operation of the engine is as follows: Assuming that the piston is turning in the direction of the arrow in Fig. 4 and that an explosion has previously taken place in the chambers 5' of the cylinder head 4, the 60 pistons will be moving toward the left as well as rotated, consequently a fresh fuel charge is being compressed in the cylinder 9 and a fresh charge is being drawn into the cylinder 10. As the piston 17 reaches the 65 end of its compression stroke one of the lugs

34 engages the lug 33 and turns the ring 21 sufficiently to admit the compressed vapor into the ports 19 and the explosion chambers 5' in the cylinder head 3. Further movement of the piston covers the ports 23 at 70 which time, the charge is ignited and the piston driven back in the opposite direction. The piston 7 is not driven forcibly against the opposite head of the cylinder as the compression of gas in the compression 75 cylinder acts as a cushion. When the piston reaches the opposite side, the above operation is repeated and so on indefinitely. To cool the cylinder, water is constantly circulated through the water jackets or 80 spaces 44 and 45 in the cylinder 1 and its heads 3 and 4 respectively.

Having described my invention what I claim as new and desire to secure by Letters Patent, is:

1. In an explosion engine a working cylinder and a piston mounted therein, said piston having a combined rotary and laterally reciprocatory movement, in combination with a shaft driven by the rotary movement of 90 the piston, and means for operating the inlet and exhaust by the lateral movement of the piston, substantially as described.

2. In an explosion engine a working cylinder having inlet and exhaust ports in combination with a shaft extending through said cylinder, a piston rotatably fixed but longitudinally movable on said shaft, said piston having a combined rotary and laterally reciprocatory movement, and means for operating the inlet and exhaust by the lateral movement of the piston, substantially as described.

3. In an explosion engine a working cylinder in combination with a compression cylinder arranged upon each side of said working cylinder and in axial alinement therewith, a shaft rotatably mounted in said cylinders, a working piston slidably mounted but rotatably fixed upon said shaft and within the working cylinder, said piston having a combined rotary and laterally reciprocatory movement, a compression piston arranged in each of the compression cylinders and longitudinally movable with the working piston, there being inlet and exhaust ports leading from said compression cylinders to the working cylinder, a valve ring arranged in each of said cylinders for controlling said ports, and means on the compression pistons 120 for operating said rings, substantially as described.

4. In a rotary explosion engine a working cylinder having a pair of cylinder heads, the inner faces of which are divided into a plurality of equal sectors angularly disposed and those upon the opposite end walls being equally and oppositely inclined, and a piston coextensive in diameter with said cylinder and comprising a plate formed of a plurality 130

of sectors conforming in number and angular arrangement to those of the end walls of the cylinder, substantially as described.

5. In a rotary explosion engine a working cylinder having a pair of cylinder heads the inner faces of which are divided into a plurality of equal sectors angularly disposed and those upon the opposite end walls being equally and oppositely inclined, and a piston 10 coextensive in diameter with said cylinder and comprising a plate formed of a plurality of sectors conforming in number and angular arrangement to those of the end walls of

the cylinders, each of the sectoral faces of the cylinder heads being provided with an 15 explosion chamber and means for exploding successive charges alternately in the chambers of the opposite heads, substantially as described.

In testimony whereof I have signed my 20 name to this specification in the presence of two subscribing witnesses.

EDMOND M. WEINAT.
